Wesley G. Carr
ATTORNEY

UNITED STATES PATENT OFFICE

OSCAR WERNER, OF SOUTH BEND, INDIANA, ASSIGNOR TO WESTINGHOUSE ELECTRIC & MANUFACTURING COMPANY, A CORPORATION OF PENNSYLVANIA

LIGHTING UNIT

Application filed June 18, 1929. Serial No. 371,765.

My invention relates to lighting units and has particular relation to a supporting device for such units.

Lighting units have been devised whereby the sockets, the lamps and the globes are so arranged and supported that the globes may be removed from the supports without disturbing the sockets. Generally, the globes of such lighting units are provided with cylindrical openings in their upper portions, and the supporting standards are provided with two or more projecting fingers to support the globes by projecting beneath suitable flanges of the globes. When the globes are in engaged position, supporting canopies or like members rest upon them to prevent them from tilting and from being disengaged from the supports.

However, such devices are so constructed that the globes are not easily removed by a single operator, and consequently, breakage of the globes frequently occurs.

My invention is intended to eliminate these and other difficulties and to provide an improved supporting device. Therefore, an object of my invention is to provide a supporting device for a lighting unit which may readily be manipulated to permit removal of the globe and disassembly of the unit.

Another object of my invention is to provide a simple, inexpensive, strong and durable device.

Other objects of my invention will appear in the following description of my device, taken in conjunction with the drawings.

Referring to the drawings, in which like figures indicate like parts,

Figure 1 is a side view, partly in elevation and partly in section, of my device, with the globe and canopy in their engaged positions, and

Fig. 2 is a side view, partly in elevation and partly in section, of my device with the canopy in a disengaged position and showing the globe being mounted upon the supporting device.

Referring to the drawings, the supporting member 1 is here shown as a tube having a threaded lower end for supporting a socket 2 for a lamp 3, the socket being fastened to

the tube or pipe by means of a nipple 4 and a bracket 5, the central portion of which engages the nipple and the outer ends of which are fastened to the socket by means of screws 6.

The globe-supporting member 7 is preferably a flat strip, of substantially U-shape, the central portion of which may have threaded engagement with the outer wall of the nipple 4 or may rest against the bracket 5. The globe-support 7 is provided with horizontally-extending end portions 8 upon which a globe 9 may rest. One or more projections, such as rivets 11, or upstruck portions of the strap or the like, are disposed on the globe-supporting member 7 intermediate its ends. The globe 9 is provided with a circular opening 12 surrounded by a flange 13 to engage, and rest upon, the end portions 8 of the support 7. The globe is placed in operating position by tilting it and placing it over one arm of the support 7. On pushing the globe upwardly, it passes over the other arm of the member 7, and, when it is moved to its normal horizontal position, both end portions 8 of the support 7 engage the flange 13 to support the globe.

If no further structure were provided, the globe might eventually become disengaged from the globe support, so that a canopy 14, which is preferably of bell-shape and has a lower flange 15, is provided with an opening 16 at its center so that it may be slidably mounted on the standard 1 and may be moved up and down or tilted thereon. When the canopy is in its lower or engaging position, the flange 15 coacts with the flange 13 to hold the globe securely in place on the support 7. The canopy is provided with a locking means, such as the nut 17, to engage threads on the nipple 4 to lock the canopy in place on the globe and support.

In its raised position, the canopy may be tilted, and the lower edge of the flange 15 may be engaged by one of the projections 11 to hold the canopy in its raised position while the globe is being removed.

The devices of the prior art have been so arranged and constructed that it was necessary for the operator to hold the canopy in

its raised or disengaged position with one hand while he tilted the globe and removed it from its support. The globes were usually large and unwieldy, and oftentimes, the 5 operator dropped them while removing or placing them on their supports.

My invention provides a simple and inexpensive device for holding the canopy in its raised position, and both hands of the operator may be utilized in holding the globe 10 while it is being placed on or taken from its support.

It is apparent that other modifications of my device may be made; for instance, the 15 support 7, instead of being a flat strip of metal, may be a member of cup shape. Instead of the projections 11, which are adapted to coact with the flange 15, projections may be placed on the inside of the canopy to coact 20 with suitable depressed portions or openings in the support. These and other modifications may be made by those skilled in the art without departing from the spirit and scope of my invention, as set forth in the appended claims.

I claim as my invention:

1. A lighting unit including a globe, a strap-like support of U-shape for the globe, a canopy for holding the globe in position on the support and means for holding the canopy in disengaged position comprising a projection on the globe support.
2. A lighting unit including a support, a canopy adapted to detachably engage the support, and means for holding the canopy in disengaged position including a means on the support to engage the flange of the canopy.
3. A lighting unit including a support, a canopy adapted to detachably engage the support and means for holding the canopy in disengaged position including coacting means on the support and the outer portion of the canopy.
4. A lighting unit including a globe, a supporting member, a strap supporting means for supporting the globe and supported, in turn, by the supporting member, a canopy of substantially bell-shape slidably mounted on the supporting member and means on the strap supporting means for holding the canopy in a raised position.
5. A lighting unit including a supporting member and globe support, a globe having an opening in its upper part for engaging the globe support, a canopy slidably mounted on the supporting member to hold the globe in place on the globe support and coacting means on the globe support and canopy for holding the canopy in a raised, disengaged position.
6. A lighting unit including a supporting member and a globe support, an electrical receptacle attached to the supporting member to receive an electric light, said recep-

70 tacle adapted to be connected to an energizing source, a globe having an opening in its upper part for engaging the globe support, a canopy slidably mounted on the supporting member to hold the globe in place on the globe support, a locking means for holding the canopy in its engaged position, and coacting means on the globe support and canopy for holding the canopy in a raised disengaged position.

75 In testimony whereof, I have hereunto subscribed my name this 7th day of June 1929.

OSCAR WERNER.
